UNITED STATES PATENT OFFICE

DAVID D. ARCHIBALD AND FRANK L. LOUANDES, OF TOLEDO, OHIO.

VALVE-GRINDING MACHINE.

1,276,705.

Specification of Letters Patent. Patented Aug. 27, 1918.

Application filed April 23, 1917. Serial No. 164,008.

To all whom it may concern:

Be it known that we, DAVID D. ARCHIBALD and FRANK L. LOUANDES, citizens of the United States, residing at Toledo, in the county of Lucas, State of Ohio, have invented certain new and useful Improvements in Valve-Grinding Machines; and we do hereby declare the following to be a full, clear, and exact description of the invention, 10 such as will enable others skilled in the art to which it appertains to make and use the same.

This invention relates to new and useful improvements in devices for grinding gas engine valve seats, and has for its primary object to provide a device of this character adapted to grind a plurality of valve seats at a single operation.

A further object of the invention is to 20 provide a device of this character which is adapted to be secured to the gas engine cylinders after the cylinder heads have been removed therefrom.

A further object of this invention is to 25 provide a device of this character which is adjustable to engines of different types and sizes.

Referring to the drawings,

Figure 1, is a side elevation of the device, 30 Fig. 2, is an end elevation, Fig. 3, is a top plan view, and, Fig. 4, is a detail sectional view on the line 4-4 of Fig. 1.

Referring more particularly to the drawings, the reference character 5 designates 35 the top face of the cylinder block after the cylinder head has been removed therefrom, and 6 represents the bolt openings in which the bolts which secure the cylinder head in 40 place engage.

In carrying out the invention, a plurality of standards 7 are employed, the lower end of which are provided with a right angular foot 8 which is perforated to receive a bolt 45 9. This bolt is adapted to engage in one of the openings 6 in the cylinder block, and threaded on the same is a nut 10 which clamps the foot member 8 of the standard 7 between itself and the cylinder block. It 50 is to be understood that there are four of the vertically extending standards 7 and that they are arranged one at each corner of the cylinder block, and connecting said vertically extending standards in pairs are 55 transversely extending bars 11. The vertically extending standards 7 are each pro-

vided with a longitudinally extending slot 12, and the transversely extending bars 11 are likewise provided each with a longitudinally extending slot 13, and passing through 60 said slots 12 and 13 is a bolt 14 by which the transversely extending bars 11 are adjusted with relation to the vertically extending standards 7 to which they are connected.

The transversely extending bars 11 are 65 each provided with a slot 14' and engaged in said slots is a longitudinally extending bar 15 which is provided with a set screw 16 by which the bar 15 is secured against movement relative to the transversely extending bar 11 when it has been properly adjusted. The longitudinally extending bar 15 is provided with a plurality of cut out 70 portions 17, and slidably mounted in each of said cut out portions 17 is a block or the like 18 which is provided with a perforation 75 and projecting through each of the sliding blocks 18 is a shaft 19 the lower end of which is tapered as at 20 to engage the top face of the valve 21. Secured to the upper 80 end of each of the shafts 19 is a gear or sprocket 22 which is secured to the shaft in such a manner as to rotate the same upon rotary movement being imparted to said sprocket. Extending vertically from each 85 end of the longitudinally extending bar 15 is a standard 23 which is adjustably secured in place by means of a set screw 24, and loosely mounted on the upper end of each of the said standards is a sprocket wheel 25, 90 while intermediate the ends of said bar 15 is a shaft 26 to the upper end of which is secured a gear or sprocket 27 which latter is provided with a squared end for the reception of the squared socket 28 of a driving crank 29. Passing around each of the sprockets 25 is a chain 30 which chain engages each of the sprockets 22 and the sprocket 27.

The operation of the device is described 100 as follows:

The vertical standards 7 are first secured to the upper end of the cylinder block, and the transversely extending bars 11 are adjusted by means of the set screws 14 to properly position the longitudinally extending bar 15. After the longitudinally extending bar 15 has been properly adjusted, the blocks 18 are adjusted so that their openings will lie substantially over the center 110 of its respective valve 21 in which position it is secured by means of a set screw 31.

With the parts in this position it will be seen that upon rotation of the crank 29, the shaft 26 will be rotated and through the medium of the chain 30, rotary movement will be imparted to each of the shafts 19, and through the medium of said shafts each of the valve members 21 will be rotated in their respective valve seats to reground the surface thereof.

10 By constructing the members 7, 11, 15, and 18, in such a manner that they are adjustable with respect to each other, it is apparent that the device is adapted for use with automobile engines of various types

15 and sizes, and that any number of shafts 19 and gears 22 may be employed for the purpose of grinding the valves of motors in which any number of valves may be employed.

20 Having thus described the invention, what is claimed is:

1. The combination with a plurality of supports adapted to be secured in spaced relation to each other upon a cylinder block, 25 of cross members adapted to be connected for vertical adjustment to pairs of said supports and having longitudinal slots therein, a longitudinal bar engaged in said slots, means for fastening the longitudinal bar in 30 its adjusted position in said slots, said longitudinal bar having a plurality of cut out portions, blocks slidably mounted in the cut out portions, means for fastening the blocks

in their adjusted positions, valve grinding members engaged in said blocks and having gears at their upper ends, and a driven endless chain supported to have the opposed parallel stretches thereof engaged with the gears at opposite sides of the same.

2. The combination with a plurality of supports adapted to be secured in spaced relation to each other upon a cylinder block, 40 of cross members adapted to be connected for vertical adjustment to pairs of said supports and having longitudinal slots therein, a longitudinal bar engaged in said slots, means for fastening the longitudinal bar in its adjusted position in said slots, said longitudinal bar having a plurality of cut out portions, blocks slidably mounted in the cut 45 out portions, means for fastening the blocks in their adjusted positions, valve grinding members engaged in said blocks and having gears at their upper ends, a driven endless chain supported to have the opposed parallel stretches thereof engaged with the gears at opposite sides of the same, and means supported by the longitudinal bar for 50 imparting movement to the chain.

55 In testimony whereof we affix our signatures in the presence of two witnesses.

DAVID D. ARCHIBALD.
FRANK L. LOUANDES.
